22 D 16834

D 16834

UNITED STATES PATENT OFFICE.

JULIUS PEGEL, OF CAMDEN, NEW JERSEY, ASSIGNOR TO JOHN BROMLEY & SONS, OF PHILADELPHIA, PENNSYLVANIA.

DESIGN FOR A RUG.

SPECIFICATION forming part of Design No. 16,834, dated August 3, 1886.

Application filed June 19, 1886. Serial No. 205,730. Term of patent 3½ years.

To all whom it may concern:

Be it known that I, JULIUS PEGEL, a subject of the Emperor of Germany, and a resident of Camden, New Jersey, have invented 5 and produced a new and original Design for Rugs, of which the following is a specification, reference being had to the accompanying photographic illustration, to which reference is made.

10 In the illustration, A is a rectangular straight-edged border to an inner large panel, B, and it is ornamented with flowers C C, in the general form of daisies, at intervals of its whole length.

15 D D is fanciful ornamentation between the border A and the edges of the rug.

E E are masses of flowers and leaves extending from near the upper right-hand corner to near the lower middle of the center 20 panel, and thence to a point near the upper left-hand corner thereof. The two lower corners from the edges of this mass of flowers are filled with the flowers and leaves. Light sprays, F F, of fern-like leaves and sprays and varied 25 leaves G and flowers H extend into the remaining space.

One of the end borders, comprising all of that part of the design outside of the central panel, is omitted from the illustration, as it would be a mere duplication of what is shown 30 outside of the other end of said central panel.

The leading features of my design will appear from the following claim.

What I claim is--

A design for rugs, consisting of the ornamental rectangular border A, middle large panel, B, masses of flowers and leaves E E, filling the lower corners of the panel B, the upper edges of the masses extending from a point near the lower middle space of panel B 35 to near the upper right and left hand corners thereof, and sprays of leaves and flowers extending into the space of the panel above the masses E E, substantially as shown and described. 40

JULIUS PEGEL.
